4 Claims. (Cl. 280—6.11)

This invention relates to a rocking bolster wagon or other type of four-wheeled vehicle wherein a non-rocking bolster is provided for the rear wheels and a rocking bolster is provided for the front or steerable wheels.

One object of the invention is to provide a rocking bolster wherein the rocking of the bolster shifts the point of contact between the bolster and the axle toward the same side that the center of gravity of the load in the wagon is displaced when travelling over uneven ground. This helps to prevent tipping and stabilizes the loaded wagon, and is particularly important in "gravity wagons" which necessarily have a high center of gravity.

Another object is to provide a comparatively simple rocking bolster structure wherein a bolster supporting member has a substantially planar supporting surface and a bolster member has a rocker element adapted to rock on such supporting surface, means being provided for confining the bolster member against endwise movement relative to the supporting member.

Still another object is to provide such means to prevent endwise movement in the form of a link having opposite ends pivoted to the supporting member and the bolster member.

A further object is to provide a double link arrangement wherein two links cooperate with each other to also prevent upward movement of the bolster member away from the supporting member, thereby retaining the rocker element of the bolster member in substantial contact with the rocker supporting surface at all times, the two links for this purpose extending in opposite directions from the ends of the bolster member toward the center of the supporting member.

Still a further object is to provide a relationship between the curvature of the rocker element, the length of the link and a curved path described by a pivot point of the link on the bolster member when it is free to rock on the supporting member, the radius of the link being equal to the radius of such curvature and the pivot point of the link to the supporting member coinciding with the center for such curvature.

With these and other objects in view, my invention consists in the construction, arrangement and combination of the various parts of my rocking bolster wagon, whereby the objects above contemplated are attained, as herein-after more fully set forth, pointed out in my claims and illustrated in detail on the accompanying drawing, wherein:

FIG. 1 is a front elevation of a gravity wagon with my rocking bolster construction applied thereto;

FIG. 2 is a line diagram illustrating the geometry of my bolster construction and showing it in the level position;

FIG. 3 is a similar line diagram showing the front axle of the wagon tipped as on an inclined surface; and

FIG. 4 is an enlarged end view of the rocking bolster construction shown in FIG. 1.

On the accompanying drawing I have used the reference numeral 10 to indicate the upper rectangular box portion of a gravity wagon, 12 the sloping front wall thereof, 14 the sloping rear wall thereof and 16 the sloping bottom wall thereof. These walls terminate adjacent a flow control door or sliding gate 18 which can be opened for permitting grain and similar commodities in the wagon body 10, 12, 14, 16 to flow by gravity into a suitable container such as a bushel basket or the like.

Due to the geometry of a "gravity wagon" its center of

gravity is relatively high. As illustrated in FIG. 1 it may be mounted at its front end on an axle 20 of the steerable type having wheels 22. The mounting disclosed comprises a bolster member 24 and a bolster supporting member 26. The member 26 has a web 28 providing a substantially planar supporting surface for a rocker element 30, secured to the lower surface of the bolster member 24. As shown in FIG. 5, the rocker element 30 is in the form of a pair of curved shoes, and the entire construction may be formed of steel welded together in an obvious manner. Uprights 25 extend from the bolster member 24 to the wagon box and can also be of welded construction. Usually there are reinforcing frame members which I omit from the disclosure in FIG. 1 because they form no part of my present invention.

The steerable axle 20 is at the front of the wagon box, and at the rear there is a suitable non-rocking bolster 24a, uprights 25a, non-steering axle 20a and wheels 22a shown in FIG. 1 by breaking away the corresponding parts 24, 25 and 22.

To complete my rocking bolster construction, I provide a front link 32 and a back link 34. These links have outer ends pivoted at A and B to the bolster member 24 and adjacent inner ends pivoted at C and D to the bolster supporting member 26. The relationship of the curvature of the rocker element 30, the length of the links 32 and 34 and the positions of the pivots A, B, C and D are quite important in my rocking bolster construction as will now be described in detail.

Referring first to FIGS. 2 and 3, the lower curved surface of the rocker element 30 is shown as a curved line 30X. The curvature 30X has a radius R. The pivot points A and C are connected by the link 32 which is here represented by radius r.

The bolster 24 is shown in central or level position in FIG. 2, and can rock to limits indicated 24X and 24Y in FIGS. 2 and 3. The surface of the web 28 on which the curvature 30X rocks is indicated at 28X and the tangent point between the two at T and T', respectively.

Assume now that the curvature 30X is free to rock on the surface 28X. It can rock to the limits dictated at 24X and 24Y. As it does this, the point A will describe an arc-shaped curvature 36 to the limits A' and A'' to which the radii r' and r'' correspond. If the center for the curvature 36 is explored, it will be found to occur at point C (where the three radii r, r' and r'' cross each other) and, accordingly, the length of r is also thus found. Therefore, if the link 32 from pivot A to pivot C is made equal to the length r the link will confine the bolster member 24 against endwise movement relative to the surface 28X except as dictated by a free rocking of the curvature 30X of the surface 28X, and there will at no time be any tendency to either lengthen or shorten the link thus avoiding any undue strain on the link or wear on its pivots.

The link 34 is a duplicate of the link 32 in the opposite direction and, accordingly, it likewise does not cause any endwise shifting of the bolster member 24 except as dictated by the rocking of 30X on 28X. The two links 32 and 34 cooperate to perform the additional function of preventing any upward movement of the bolster member 24 and thereby the rocker element 30 away from the web 28 of the rocker supporting member 26.

FIG. 2 shows a complete diagram including lines 22X representing the wheels 22 resting on a ground surface indicated at 38, point CWG being the center between wheels at the ground surface. If the ground surface for the front wheels 22 tips as shown at 38a in FIG. 3 while the rear wheels and therefore the wagon box remain level, then CWG shifts distance d to the right as illustrated from the vertical bolster center line 40. The tangent point T of FIG. 2 now becomes T' of FIG. 3, and it will be noted

has likewise shifted to the right a slightly greater distance d' . This helps to prevent tipping and effects greater stabilization of the loaded wagon. It is thus obvious that the rocking arrangement disclosed produces improved results from the standpoint of better control of the load as the wagon travels over uneven ground.

From the foregoing specification it will be obvious that I have provided a comparatively simple rocker and linkage arrangement wherein the links prevent undesirable endwise movement of the bolster member relative to the bolster supporting member and also upward movement of the bolster member away from the bolster supporting member, yet at the same time permit smooth rocking action. At the same time, the linkage is so selected relative to the radius R in FIGS. 2 and 3 that free rocking movement of the rocker element on the surface $28X$ results thus eliminating any sliding action and, accordingly, wear as between the two, and results in substantially no strain on the pivots A, B, C and D due to the relationship of parts as disclosed. Obviously, the radius R can be increased or decreased as desired and the resulting pivot points A and C varied accordingly to the resulting arc 36. The resulting structure consists of merely the bolster-rocker member, its supporting member, and a pair of links pivoted to the two and serving to act in the capacity outlined. Relatively simple steel shapes can be used for fabricating the bolster construction and a few simple welds serve to rigidly connect the parts together for trouble-free operation and long life.

The shifting contact or point of tangency of my rocking bolster tends to stay over the point CWG thus removing much of the strain from the frame and body of the wagon. The bolster member "rocks uphill" at any time that the front and rear axles are not in the same plane. The resulting bolster action is especially valuable in a semimonocoque construction such as is generally used in gravity wagons.

Some changes may be made in the construction and arrangement of the parts of my rocking bolster wagon without departing from the real spirit and purpose of my invention, and it is my intention to cover by my claims any modified forms of structure or use of mechanical equivalents which may reasonably be included within their scope.

I claim as my invention:

1. In a rocking bolster wagon, a bolster member, a bolster supporting member having a substantially planar supporting surface, a rocker element on said bolster member adapted to rock on said supporting surface, and means for confining said bolster member against endwise movement relative to said supporting member comprising a pair of substantially horizontal links, one end of each link being pivoted to said supporting member adjacent the outer ends thereof whereby said links extend from opposite ends of said supporting member toward the center of said bolster member, and the other end of each link being pivoted to said bolster member adjacent the center thereof, said links being operable to also prevent upward movement of said bolster member away from said supporting member and thereby retain said rocker element in substantial contact with said supporting surface at all times.

2. In a rocking bolster wagon, a bolster member, a bolster supporting member having a substantially planar supporting surface, a rocker element on said bolster member adapted to rock on said supporting surface, means for confining said supporting member comprising a link having opposite ends thereof pivoted to said supporting member and said bolster member, the pivot point of said link to said bolster member describing a curved path when said bolster member is free to rock on said supporting surface, the radius of said link being equal to the radius of such curvature and the pivot point of said link to said supporting member coinciding with the center for such curvature.
3. In a rocking bolster wagon, a bolster member, a bolster supporting member having a substantially planar supporting surface, a rocker element on said bolster member adapted to rock on said supporting surface, means for confining said bolster member against endwise movement relative to said supporting member comprising a pair of links having opposite ends pivoted to said supporting member and said bolster member, said links extending from opposite ends of said bolster member toward the center of said supporting member, said links being operable to also prevent upward movement of said bolster member away from said supporting member and thereby retain said rocker element in substantial contact with said supporting surface at all times, the pivot points of said links to said bolster member describing curved paths when said bolster member is free to rock on said supporting surface, the radii of said links being equal to the radii of such curvatures and the pivot points of said links to said supporting member coinciding with the centers for such curvatures.
4. In a rocking bolster wagon, a bolster member, a bolster supporting member having a substantially planar supporting surface, a rocker element on said bolster member adapted to rock on said supporting surface, and means for confining said bolster member against endwise movement relative to said supporting member comprising a pair of substantially horizontally extending links having outer ends pivoted to said bolster member adjacent the ends thereof and inner ends pivoted to said supporting member adjacent the center thereof, the radii of said links being so related to the radius of said rocker element, and the pivot points of said links to said supporting member and said bolster member being so related to said radii that free rocking motion of said rocker element of said bolster member relative to said supporting member is had without said links imparting any endwise sliding movement to said rocker element relative to said planar supporting surface.
